UNITED STATES PATENT OFFICE.

ROYAL E. MILLER, OF CHICAGO, ILLINOIS, ASSIGNOR TO THE ADLAKE COMPANY, A CORPORATION OF ILLINOIS.

DAMPER FOR VENTILATORS.

Application filed June 11, 1926. Serial No. 115,236.

The invention relates to dampers for ventilators, such as are being applied to the roofs of automobiles, and in connection with which the dome lamp is mounted.

5 The objects of the invention are to secure simplicity of construction, durability and convenience of operation.

An embodiment of the invention is hereinafter described, and is illustrated in the 10 accompanying drawings, in which

Fig. 1 is a detail vertical longitudinal section of the roof of a vehicle and a ventilator and the improved damper applied thereto;

Fig. 2 is a plan view of the improved device detached from the vehicle;

Figs. 3 and 4 are detail sectional views taken on the lines 3—3 and 4—4, respectively, of Fig. 2; and

Fig. 5 shows segmental details of three 20 of the parts of the device.

The roof of a vehicle is represented at 10, and as being provided with a ventilating aperture 11, above which is mounted a ventilating device 12 of any preferred form.

25 The dome lamp and damper usually conform in shape and form a closure for the aperture 11. In the illustrated embodiment of the invention this aperture is circular, and the device is given the same form.

30 A circular plate 13, of slightly greater diameter than the aperture 11, is secured to the lower face of the vehicle top 10 by any suitable means, such as the screws 14. This plate is preferably flanged upwardly at its

35 periphery, as shown at 15, to space it from the wall surface, and apertured bosses, as 16, are formed or applied to its upper surface immediately within the flange 15 and registering with the apertures for the screws 14.

40 Centrally the plate 13 is curved upwardly, as indicated at 17, to stiffen the plate, provide a lamp chamber and to constitute a reflecting surface.

A ring 18 depends from the plate 13 and 45 surrounds its curved portion 17 to form an extension of the lamp body and to carry the glass front 19 thereof. The inner face of the lower portion of the ring 18 is concave to receive a glass-holding ring 20. The ring 50 is secured to the plate 13 by means of integral lugs, as 21, which project through suitable apertures in the plate, their upper ends being bent down upon the surface of the

plate, as plainly shown in Fig. 3. The reflector 17 is apertured to receive and hold a 55 lamp socket 22.

An annular series of apertures, as 23, is formed in the portion of the plate 13 lying between the reflector 17 and the area within which the screw openings are provided, and 60 outside of this series of openings the plate is channeled in its upper surface, as indicated at 24. An annular register plate 25, apertured, as shown at 26, to correspond with the apertures 23, is slidably mounted 65 upon the apertured portion of the plate 13, and is provided with a depending flange 27 which fits and freely slides within the channel 24 of the plate 13. The ring 18 is also provided with a series of upstanding lugs 70 28, which project through suitable apertures in the plate 13, and are folded down against the upper surface of the register plate 25, to frictionally hold it in engagement with the plate 13. 75

A controlling knob, as 29, depends below the plate 13, its stem being fixed in the register plate 25, and the plate 13 being slotted, as shown at 30, to permit its movement for the purpose of shifting the register plate 80 to bring its apertures into or out of register with the apertures in the damper plate. The register plate 25 may be provided with suitable notches or cut-away portions, as 31, to accommodate the ring-attaching lugs 21, 85 and in its outer margin is cut away, as indicated at 32, to accommodate the bosses 16 and permit the necessary plate movement.

The damper is readily opened or closed by means of the controlling knob 29. 90

While a simple and efficient form of construction is disclosed, various changes of detail may be made without departing from the scope of the invention.

I claim as my invention— 95

1. A damper for ventilators comprising a fixed plate having an annular series of apertures, an annular plate in slidable contact with the fixed plate and having an annular series of registering apertures, one of such 100 plates having a circular guide groove outside of its apertures and the other plate having a guide rib complementary to and seated in the groove and lugs attached to the fixed plate and overlapping the inner 105 margin of the slidable plate for holding the

two plates in contact and guiding the slide-
able plate.

2. A damper for ventilators comprising a
plate having an annular series of apertures
and an annular channel in its upper face, a
register plate slidably mounted on the first-
named plate and having a series of apertures

for registering with the apertures thereof, a
rib complementary to and seated in the
channel, and clips rising above the first-
named plate and overlapping the register
plate.

In testimony whereof I affix my signature.

ROYAL E. MILLER.
